UNITED STATES PATENT OFFICE.

JOSEPH E. BLOOMBERG, OF MILWAUKEE, WISCONSIN.

SHOE JACKET.

Application filed May 18, 1927. Serial No. 192,343.

The invention relates to shoe jackets for wear over skating shoes.

The object of the invention is to provide a simple but effective heat-retaining shoe jacket which can be readily applied to the exterior of a skate-carrying shoe, and which will also serve to prevent the commonly-used skate strap from causing uncomfortable localized pressure on the foot.

10 The invention further consists in the several features hereinafter set forth and more particularly defined by the annexed claims.

In the accompanying drawings,

Fig. 1 is a side elevation of a skate-carrying shoe having applied thereto a shoe jacket embodying the invention;

Fig. 2 is a similar view of a modified form of shoe jacket;

Fig. 3 is a top plan view of the skate with the shoe jacket in place;

Fig. 4 is a sectional view taken along the line 4—4 of Fig. 1, and

Fig. 5 is a transverse sectional detail view of the shoe jacket taken on the line 5—5 of Fig. 1.

25 In these drawings, the numeral 10 designates an ice skate of conventional type including the usual pillars 11, 12 and 13, permanently attached to the bottom of a skating shoe 14, the pillars 11 and 12 being of hollow tubular construction and the shoe 14 being provided with the usual front lacing 15 for closing the shoe on the foot.

35 In that form of the invention shown in Fig. 1 the shoe jacket or cover comprises a lined upper 16 secured to a bottom 17, the upper covering the shoe 14 from toe to heel in the manner of an overshoe, and the bottom 17 engaging the bottom or sole of the shoe 14; while in that form of the invention shown in

40 Fig. 2 the upper 16' and bottom 17' cover only the forward portions of the shoe. In each instance the upper is formed of complementary right and left halves, which are joined at their forward toe portions by a sewn leather strip 18, and the remaining parted forward portions of the upper are joined by a lacing 19, there being a gusset 19' under the lacing. The interior of the upper is lined with a suitable heat-insulating material 20, preferably

45 sheepskin, and this is preferably finished at exposed edges by binding 21. The upper 16 is secured to the bottom 17 in any suitable manner, such as indicated in Fig. 5, and the bottom 17 is provided with a central longitudinal slit 22 which extends the entire length of the bottom except for that portion of the

bottom forward of the front skate pillar 13, the upper 16 having a slit 22' down its rear portion communicating with the slit 22. The slit 22 merges at intervals with enlarged openings 23, 24 and 25, the edges of which fit closely about the skate pillars 11, 12 and 13, and the interior of the bottom is provided with a lining 26 sewn thereto to provide both reinforcement and additional heat insulation. 60 65

In order to close the bottom 17 of the shoe jacket along the sole of the skate shoe, the bottom 17 is provided along its parted edges with hooks 27 receiving a crossed lacing 28 which passes on opposite sides of the skate 70 pillars 11 and 12 and is tied preferably at the forward end of the skate. For closing the rear parted portions of the upper 16 about the rear portion of the skate shoe 14 transverse flaps 29 are sewn to one side of the upper and carry glove fasteners 30, as seen in Figs. 1 and 3, at the other side of the upper. 75

In applying the shoe jacket of Fig. 1 to the shoe, the lacing 19 is opened, the fasteners 30 are unclasped, and the lacing 28 at the bottom 80 of the jacket is removed. The shoe jacket may then be spread laterally and embraced about the skate shoe, the glove fasteners 30 being then closed, and the lacing 28 being engaged along the bottom hooks 27 to substantially close the gap along the bottom. The operation is similar with the shoe jacket of Fig. 2, except that the clasps are omitted and the jacket is prevented from becoming displaced since the enlarged openings in the bottom 90 closely surround the forward skate pillars 12 and 13. When placing the skate shoe on the foot the usual front lacing 15 of the shoe is opened, as well as the front lacing 19 of the shoe jacket, and these lacings are then 95 closed in succession.

When it is desirable to employ a skate strap 31, the forward portion of the strap bears against the lined upper of the shoe jacket, thereby preventing uncomfortable localized 100 pressure on the foot. When removing the skate shoe from the foot, the lacings 19 and 15 are opened in succession and the shoe jacket can be left on the skate.

By means of the shoe jacket of this invention the feet may be kept warm while skating, and it is then possible to use skate shoes that fit properly on the feet since no allowance need be made for the use of several pairs of socks. The shoe jackets also protect the 105 shoes and feet against injury by the skate blades of other skaters. Since the shoe jack-

ets are of such construction that they can be secured snugly and firmly in place on the skate shoes, the ankles are given additional support, thereby dispensing with the use of 5 ankle braces.

What I claim as new and desire to secure by Letters Patent is:

1. The combination, with a shoe having a 10 skate thereon, of a shoe jacket comprising a lined upper receiving said shoe, a bottom secured to said upper to substantially cover the sole portion of the skate shoe and parted longitudinally for receiving skate elements therethrough, and a lacing for securing said 15 parted bottom sections about said skate elements.

2. The combination, with a shoe having a 20 skate thereon including spaced supporting pillars permanently attached to the sole of said shoe, of a shoe jacket comprising a lined upper receiving said shoe, a bottom secured to said upper and parted longitudinally to 25 closely surround said pillars, and means for securing together the parted portions of said bottom.

3. The combination, with a shoe having a 30 skate thereon, of a shoe jacket comprising a lined upper receiving said shoe and having a closable top opening, a bottom secured to said upper to substantially cover the under surface of the skate shoe and parted longitudinally for receiving skate elements therethrough, the opening between said parted bottom sections continuing upwardly along 35 the rear of said upper, and means for securing together the parted portions of said bot-

tom and the rear parted portions of said upper.

4. The combination, with a shoe having a 40 skate thereon, of a shoe jacket comprising a heat-retaining upper receiving said shoe and having a closable top opening, adjustable means for closing said opening, and a bottom 45 secured to said upper to substantially cover the sole portion of the skate shoe and secured together along said sole portion, whereby said jacket may be secured in snugly fitting engagement with said shoe to form an additional bracing means for the foot.

5. The combination, with a shoe having a 50 skate thereon, of a shoe jacket comprising a heat-retaining upper receiving said shoe and having a closable top opening, adjustable means for closing said opening, a bottom 55 secured to said upper to substantially cover the sole portion of the skate shoe, said bottom being longitudinally slotted along its central portion to receive skate elements therethrough, and means for securing together the slotted portions of said bottom 60 along said sole portion.

6. The combination, with a shoe having a 65 skate thereon, of a shoe jacket comprising a lined upper receiving said shoe therein, a bottom secured to said upper to substantially cover the sole portion of the skate shoe and being parted longitudinally for receiving 70 skate elements therethrough, and detachably fastening means for securing the parted bottom sections along said sole portion and about said skate elements.

In testimony whereof, I affix my signature.
JOSEPH E. BLOOMBERG.
